UNITED STATES PATENT OFFICE

2,666,212

MOBILE ELEVATOR FOR INVALIDS

Roy A. Flanders, Pratt, Kans.

Application January 6, 1951, Serial No. 204,716

8 Claims. (Cl. 5—86)

1

This invention relates to a mobile elevator for handling and transporting invalids and has for its principal objects to provide an apparatus of this character which is of simple, light-weight construction, safe in operation, and easily manipulated.

Other objects of the invention are to provide a seat suspendedly supported over a relatively narrow wheel supported base to pass through standard size doorways and which is stable when the seat is located directly thereover as when an invalid is being moved from one place to another; to provide the apparatus with stabilizing arms that are adapted to be projected laterally from the sides of the carriage so as to prevent tipping when the seat is swung laterally over a bed or the like; to provide the apparatus with means for stabilizing the apparatus when the stabilizing arms cannot be used; to provide the apparatus with a simple easily operated hoisting mechanism that holds the invalid's seat in elevated position; and to provide means for controlling tendency for the seat to swing out of its balanced position over the carriage.

In accomplishing these and other objects of the invention as hereinafter pointed out, I have provided improved structure, the preferred form of which is illustrated in the accompanying drawings wherein:

Fig. 1 is a perspective view of a mobile elevator constructed in accordance with the present invention and showing the invalid's support in suspension laterally of the mobile base.

Fig. 2 is a plan view of the elevator but with the stabilizing arms in folded position as when the foot pedal is used in lieu thereof for preventing tilting of the base under weight of an invalid.

Fig. 3 is an enlarged vertical section through the mobile base and the lower portion of the standard, particularly illustrating the ball mounting of the post which carries the invalid's support or chair.

Fig. 4 is an enlarged section through the upper portion of the elevator particularly illustrating the tackle mechanism for raising and lowering the invalid's chair or support.

Fig. 5 is a side elevational view of the base showing the stabilizing arms in folded position as when the device is to be moved through a doorway or the like.

Fig. 6 is a fragmentary perspective view showing the removable mounting for one of the stabilizing arms.

Fig. 7 is a horizontal section on a line 7—7 of Fig. 3, particularly illustrating the stops and notches on the latch collar.

2

Fig. 8 is a perspective view of the foot operated stabilizing lever and the flexible connector which connects the lever with the top of the standard.

Fig. 9 is a perspective view of the latch mechanism for preventing rotation of the invalid's support carrying post and its standard.

Fig. 10 is a detail fragmentary view particularly illustrating the slide bolt for retaining one of the stabilizing arms in extended position.

Referring more in detail to the drawings:

Fig. 1 designates a mobile elevator constructed in accordance with the present invention and which includes an elongated base or frame 2 having a cross rail 3 connecting the ends of outwardly diverging side rails 4 and 5, the inner ends of the side rails being connected with the cross rail at points inset from the ends thereof. The outer ends 6 and 7 of the side rails are spaced apart substantially in conformity with the length of the cross rail 3 as best shown in Fig. 2. Connected with the ends 6 and 7 of the side rails are caster wheels 8 and 9 which cooperate with caster wheels 10 and 11 that are mounted on the outer ends of the cross rail 3 to support the base frame.

Fig. 2 is a plan view of the elevator but with the stabilizing arms in folded position as when the foot pedal is used in lieu thereof for preventing tilting of the base under weight of an invalid.

Fig. 3 is an enlarged vertical section through the mobile base and the lower portion of the standard, particularly illustrating the ball mounting of the post which carries the invalid's support or chair.

Fig. 4 is an enlarged section through the upper portion of the elevator particularly illustrating the tackle mechanism for raising and lowering the invalid's chair or support.

Fig. 5 is a side elevational view of the base showing the stabilizing arms in folded position as when the device is to be moved through a doorway or the like.

Fig. 6 is a fragmentary perspective view showing the removable mounting for one of the stabilizing arms.

Fig. 7 is a horizontal section on a line 7—7 of Fig. 3, particularly illustrating the stops and notches on the latch collar.

The lower end of the standard 18 is closed by a plate 20 which seats a ball 21 for supporting the lower end of a post 22 which is rotatably mounted within the tubular standard and has a projecting upper end 23 carrying a laterally extending arm 24.

The lower portion of the post 22 is of a diameter to provide a close rotating fit within the tubular standard so as to position the arm 24 above the forward portion of the base frame or laterally to either side thereof as later to be described.

In order to provide a relatively strong light-weight structure, the sides and cross rails of the base frame are preferably of tubular stock having ends fitted and welded together. The post 22 may also be formed of an outer section of pipe 25 that extends substantially the full

length thereof and an inner section of pipe 26 tightly fitting within the pipe 25 and which is welded therein to form a unitary structure. The inner section of pipe has its upper end bent laterally as at 27 to provide the laterally projecting arm 24.

Mounted on the outer end of the arm is a cap 28 which carries an eye 29 to suspend a tackle mechanism 30 including an upper pulley block 31 and a lower pulley block 32, the upper pulley block being connected with the eye by a safety hook 33. A cable 34 is reeved over the respective pulleys with one end 35 anchored to the lower pulley block 32, as indicated at 36 in Fig. 4. The cable is reeved so that the other end comes off the upper pulley block 31 on the upper side of one of the pulley thereof, therefore, to prevent movement of the pulley blocks out of vertical alignment under a lateral pull on the cable. The lateral arm 24 carries a bracket 37 having a portion 38 extending downwardly alongside of the upper pulley block 31 to carry a lower guide pulley 39 under which the cable operates to exert the desired directional pull on the cable. The operating end of the cable extends upwardly from the pulley 39 and over a guide pulley 40 that is also carried by the bracket 37 at a point adjacent the upper portion of the pulley block 31 as shown in Fig. 4. From the guide pulley 40, the cable extends along the arm 24 and then downwardly over a guide pulley 41 that is carried by a bracket 42 which is located on the arm 24 at a point adjacent the vertical portion of the post as best shown in Fig. 4.

The tackle is actuated by a winding mechanism 43 that is carried on the vertical portion of the post by a bracket 44. The winding mechanism 43 includes a housing 45 enclosing a suitable speed reduction gearing which preferably comprises at least one set of worm and worm gears so that the driven shaft 46 is non-rotatable under retractive pull of the cable. The operating end of the cable is attached to a reel or spool 47 which has a fixed mounting on the shaft 46. The speed reduction gearing also includes a power shaft 48 carrying a hand wheel 49 by which the shaft may be rotated to turn the reel 47 in either direction depending upon the direction of rotation of the hand wheel.

The pulley block 32 suspendedly carries an invalid's support or chair 50 which may be of any suitable type. In the illustrated instance, the support includes a cross bar 51 having a central eye 52 that is connected with the pulley block 32 by a safety hook 53. Fixed to the outer ends of the cross bar are hooks 54 and 55 carrying chains 56 and 57 attaching a sling type seat 58 and which comprises a web 59 having hemmed ends 60 and 61 to provide loops for passing rods 62 and 63 to which the ends of the chains 56 and 57 are connected.

The cross bar 51 may be provided with handles 64 and 65 by which an invalid seated in the chair may stabilize and support himself while the elevator is being moved from place to place as later described.

In order to prevent swinging of the invalid support on the lateral arm 24 while the elevator is being moved from one place to another, the lower pulley block 32 and reeved portions of the cable are enclosed in a tubular housing 66 which is rigidly attached to the arm 24 by a strap-like bracket 67 extending over the cap 28 and having depending ends 68 and 69 attached to opposite sides of the upper end of the tubular housing as

shown in Figs. 1 and 4. Formed in the lower end of the tubular housing are pairs of diametrically opposed notches 70 and 71 to receive the upper edge of the cross bar when the invalid's chair is raised to its uppermost and carrying position as later described. The upper end of the tubular housing is provided with a slot 72 through which the cable plays as shown in Fig. 4.

With the structure thus far described, it is obvious that when the arm 24 is carried forwardly over the base, the invalid is supported over the base and the structure is stable and may be moved from place to place without danger of tipping under the weight of the invalid. However, when the arm is turned to project laterally over one or the other sides of the base, as when lifting an invalid from a bed, the weight overbalances the base and the device will tip. To avoid this difficulty, the base is provided with stabilizing arms 73 and 74 each including a rigid section of pipe 75 having its inner end pivotally connected with a pintle 76 by rule joint connections 77. The outer ends of the arms carry caster wheels 78 which cooperate with the main caster wheels in promoting maneuverability of the base, as later described.

The pintles 76 are removably mounted to carry the stabilizing arms on either one or the other sides of the base depending upon the side on which they are to be used. This is effected by providing the side rails with transversely arranged socket members 79-80 and 81-82, the socket members 79 and 81 being supported on the ends of a cross bar 83 that is supported from the cross bar 3 by a plate 84, see Figs. 1, 2, and 3. The other socket members 80 and 82 are carried by plate-like brackets 85 that are welded within the offsets of the side rails as best shown in Figs. 1 and 3. The pintles of the respective stabilizing arms are inserted within the desired socket members and are secured therein by removable pins 86 (see Fig. 6) that are inserted through openings 87 in the socket members and registering openings 88 in the pintles. The pins 86 thus support the pintles with the pivotal axis of the rule joints 77 at a slight angle to each other whereby the stabilizing arms may break inwardly toward each other and be positioned alongside of the base frame so that the caster wheels 78 will be raised slightly from the floor as indicated at 79, as best shown in Fig. 5, so that the elevator may be moved, without interference of said caster wheels, through a relatively narrow doorway or into a position where the elevator is alongside of a bathtub or the like, as later described.

The stabilizing arms may be locked in extended position by bolts 89 that are slidably mounted in sleeves 90 that are attached to the rigid portions of the arms and which engage openings 91 that are provided in the bracket plates 85 or in sleeves 92 that are attached to the socket members that are carried by the ends of the cross bar 83.

A latch means is provided for locking the post in fixed position when the arm is extended over the base or swung laterally to either side of the base as now to be described.

Fixed to the post 22 above the terminal end of the tubular standard 18 is a collar 93 having laterally projecting ears 94 carrying a pivot pin 95 for a latch lever 96 which includes a handle portion 97 that extends upwardly alongside of the post and a depending pawl portion 98 that extends downwardly to engage in one or the other 75 of a series of notches 99, 100, and 101 provided

in a collar 102 which is rigidly fixed to the upper end of the standard. The collar is positioned with the notches 99 and 101 at the sides of the standard and the notch 100 in the fore and aft direction of the base. The latch is normally retained in position for the pawl 98 to slide into one of the notches by a spring 103 which has one end engaging over a pin 104 carried by the post and its opposite end engaging over a pin 105 carried by the handle portion 97 of the latch lever 96 as best shown in Fig. 9. In order to limit turning of the post, the collar 102 is provided with stop lugs 106 and 107 so that when the invalid support is turned to the limit of its lateral positions, the pawl 98 will strike one or the other of the limit lugs and drop into the adjacent retaining notch at that side of the collar.

Located at the upper end of the standard 18 below collar 102 is a collar 108 provided with diametrically opposed hooks 109 which receive a ring 110 attached to the free end of a chain 111. The other end of chain 111 is secured to the foot 112 of a stationary stabilizing arm 113. The stabilizing arm 113 is formed of pipe 114 having the foot 112 secured to one end and a yoke 115 at the other end which removably engages the depending portions 12 and 13 of side rails 4 and 5 to provide further support for standard 18 for a purpose later described.

In using the device for lifting an invalid, for example from a bed, the chains 56 and 57 are disengaged from the hooks 54 and 55 so that the web 59 of the seat may be placed under the invalid. The stabilizing arms 73 and 74 are then extended laterally and the arm 24 is swung over the bed so that when the device is pushed alongside the bed, the stabilizing arms 73 and 74 project thereunder and the arm 24 extends over the bed. When the arm 24 is swung to the position illustrated, the latch 96 locks the post 22 from turning movement in the standard 18. The hand wheel 49 is then rotated in the proper direction to lower the cross bar 51 so as to reconnect the chains 56 and 57 with the hooks 54 and 55. The invalid grasps the handles 64 and 65 to stabilize himself on the seat. The hand wheel 49 is then rotated to wind the cable 34 on the reel 47 to raise the invalid from the bed. The invalid is then turned so that the cross bar 51 enters the notches 70. The latch 96 is then released and the arm 24 is swung to a position which carries the invalid over the base frame. The elevator is then moved away from the bed and the stabilizing arms 73 and 74 are moved into position alongside the base frame as shown in Fig. 2. In this position the wheels 78 are raised from the floor, as indicated in Fig. 5. The invalid is then carried by pushing the base frame over the floor.

Since the base frame is relatively narrow, it will pass through doors and narrow hallways. However, the carrying position of the invalid directly over the forward portion of the base frame provides stability while the invalid is being transported.

If the invalid is to be deposited in a bathtub or other place where the stabilizing arms 73 and 74 cannot be used, they may be left in folded position so that the base frame may be moved alongside of the tub. The foot lever is then placed with the yoke 115 bearing, for example, against a side rail 5 and the ring 110 of the chain 111 is engaged with the hook 109. The foot of the attendant is then placed on the pedal 112 so that when the latch 96 is disengaged and the arm 24 is swung to a lateral position with the invalid

supported over the tub, the base frame will not tilt. The hand wheel 49 is then rotated to lower the cross bar 51 out of engagement with the notches 70 whereupon the invalid may be turned to a proper position in the tub as the seat is lowered.

Attention is directed to the fact that due to the speed reducer 43, the invalid is supported in any elevated position without the use of a brake.

From the foregoing, it is obvious that I have provided a mobile elevator that is safe and easy to operate and which is of relatively light weight and simple construction. It is therefore especially suited for use in the home or hospital in handling invalids and other patients that are incapable of moving themselves from one place to another.

What I claim and desire to secure by Letters Patent is:

1. A mobile elevator of the character described including a wheel supported base, a standard on the base, a post having journalled support by the standard and having a laterally extending arm, a cable winding mechanism mounted on the post, an invalid's support including a cross member, a tackle connected with the laterally extending arm for suspending the invalid's support from said arm and including a cable connected with said cross member and with said cable winding mechanism to raise and lower the invalid's support, and a tubular housing rigidly connected with said arm and surrounding the portion of the tackle which suspends from said arm and having portions for engaging the cross member in one position of the invalid's support to prevent swinging of said support on the arm.

2. A mobile elevator of the character described including a wheel supported base, a standard on the base, a post having journalled support by the standard and having a laterally extending arm, a cable winding mechanism mounted on the post, an invalid's support including a cross member, a tackle connected with the laterally extending arm for suspending the invalid's support from said arm and including a cable connected with said cross member and with said cable winding mechanism to raise and lower the invalid's support, a tubular housing rigidly connected with said arm and surrounding the portion of the tackle which suspends from said arm and having portions for engaging the cross member in one position of the invalid's support to prevent swinging of said support on the arm, and means for selectively engaging the post with the standard to prevent turning of the post relatively to the standard.

3. A mobile elevator of the character described including a wheel supported base, a standard on the base, a post having journalled support by the standard and having a laterally extending arm, an invalid's support carried by said arm, a foot lever, means removably connecting the foot lever with the base, and a flexible connection between the standard and the foot lever, said foot lever and flexible connection being adapted to stabilize the base when the invalid support is swung laterally from a side of the base opposite the foot lever and when a downward pressure is applied to said foot lever.

4. A mobile elevator of the character described including an elongated base, caster wheels supporting the base at ends thereof, a standard extending upwardly from the base, a post having journalled support by the standard and having a laterally extending arm, an invalid's support, a pair of tackle blocks, one being connected with

the arm and the other with the invalid's support, a cable reeved over the tackle blocks, a cable winding mechanism carried by the post including a reel to which an end of the cable is connected and on which said end of the cable is adapted to be wound, a housing carried by the arm and forming an enclosure for the tackle block carried by the invalid's support, said housing having means adapted to engage a part of the invalid's support to prevent swinging of the invalid's support on said tackle when the invalid's support is in its uppermost position.

5. A mobile elevator of the character described including an elongated base, caster wheels supporting the base at ends thereof, a standard extending upwardly from the base, a post having journalled support by the standard and having a laterally extending arm, an invalid's support, a pair of tackle blocks, one being connected with the arm and the other with the invalid's support, a cable reeved over the tackle blocks, a cable winding mechanism carried by the post including a reel to which an end of the cable is connected and on which said end of the cable is adapted to be wound, pulleys supported by the arm for guiding the cable to the cable winding reel, and a housing carried by the arm and forming an enclosure for the tackle block carried by the invalid's support, said housing having means adapted to engage a part of the invalid's support to prevent swinging of the invalid's support on said tackle when the invalid's support is in its uppermost position.

6. In a mobile elevator of the character described, a base frame including a cross rail, caster wheels carrying ends of the cross rail, spaced side rails connected with and diverging from the cross rail and having outer ends, caster wheels carrying the outer ends of the side rails, said side rails having intermediate depending portions, cross rails connecting said depending portions of the side rails, a longitudinal rail connecting the last named cross rails, a standard carried by the longitudinal rail, socket members carried at the ends of the side rails, stabilizing arms removably supported in the socket members to extend laterally from the base frame, and caster wheels carried by the stabilizing arms.

7. In a mobile elevator of the character described, a base frame including a cross rail, caster wheels carrying ends of the cross rail, spaced side rails connected with and diverging from the cross rail and having outer ends, caster wheels carrying the outer ends of the side rails, said side rails having intermediate depending portions, cross rails connecting said depending portions of the side rails, a longitudinal rail connecting the last named cross rails, a standard carried by the longitudinal rail, socket members carried at the ends of the side rails, stabilizing arms removably supported in the socket members to extend laterally from the base frame, and caster wheels carried by the stabilizing arms having hinge joints on which the stabilizing arms are adapted to be moved from a position alongside said base frame to said lateral positions.

8. In a mobile elevator of the character described, a base frame including a cross rail, caster wheels carrying ends of the cross rail, spaced side rails connected with and diverging from the cross rail and having outer ends, caster wheels carrying the outer ends of the side rails, said side rails having intermediate depending portions, cross rails connecting said depending portions of the side rails, a longitudinal rail connecting the last named cross rails, a standard carried by the longitudinal rail, a foot lever, a yoke on one end of the foot lever engaging one of the side rails, and a flexible connection between the upper end of the standard and the foot lever for cooperating with the foot lever to stabilize the standard when weight is applied to the foot pedal.
